UNITED STATES PATENT OFFICE.

FORREST FERGUSON, OF ST. LOUIS, MISSOURI, ASSIGNOR, BY MESNE ASSIGNMENTS,
TO WYNNE FERGUSON, TRUSTEE, OF NEW YORK, N. Y.

OVERALLS.

Application filed September 19, 1923. Serial No. 663,613.

This invention relates to overalls, and has for its object to provide a novel method of reinforcing the lower ends of the side vents in the legs of a pair of overalls.

5 To this end I have devised a pair of overalls in which the facing pieces of the rear sides of the front pockets are provided with integral extensions that extend across the lower ends of the side vents in the legs in 60
10 such a way that they serve as reinforcing devices which effectively prevent the side seams of the legs from ripping when they are subjected to abnormal strains.

Figure 1 of the drawings is a perspective view of a portion of one leg of a pair of overalls constructed in accordance with my invention.

Figure 2 is a plan view of the facing piece of the left hand front pocket.

20 Referring to the drawings, A and B designate the front and rear portions of the left leg of a pair of overalls, C designates the side seam which joins the portions A and B together, and D designates the usual side 25 vent in the leg whose lower end terminates at the upper end of the side seam C. The overalls are provided with two front pockets each of which is formed by a piece of material folded so as to form the front portion 30 1 and the rear portion 2 of the pocket. The side edge of the front portion 1 of the pocket is faced by the piece of material that constitutes the front portion A of the leg, which piece of material is folded 35 over the side edge of the front portion 1 of the pocket and secured to same by one or more rows of stitches, as shown in Figure 1. The rear portion 2 of said pocket is faced by a facing piece E that is superimposed 40 upon the front side of the rear portion 2 of the pocket and folded over the longitudinal side edge of same, so as to serve as a binding for said edge, the inner edge of said facing piece E being secured to the 45 rear portion 2 of the pocket by one or more vertical rows of stitches and the outer edge portion of said facing piece which is doubled or folded over the side edge of the rear portion 2 of the pocket being secured to same by one or more vertical rows of stitches α .

50 In order to reinforce and strengthen the side seam C and prevent said side seam from ripping in the event the lower end of the side vent D is subjected to an abnormal strain, as, 55 for example, by the user's foot striking

against the crotch or lower end of said side vent in the operation of drawing on the overalls, I have provided the facing piece E of each front pocket with an integral extension E' that extends across the lower end 60 or the crotch of the vent D and upwardly along the rear portion B of the leg that forms the rear side of the vent D. The extension E' of the facing piece E is made wide enough to permit it to be folded under or doubled over so as to provide a plurality of thicknesses of material at the point where said extension E' is connected by stitches γ 65 to the rear portion B of the leg. The extension E' may be of any preferred length, but 70 in most instances the upper end of same will terminate at the upper edge of the adjacent hip pocket F so that the upper end of the extension E' can be secured by one or more rows of stitches β , such as are generally used 75 at the ends of a pocket to prevent the pocket from ripping.

My invention adds practically nothing to the cost of a pair of overalls, but it greatly 80 improves such garments, because the extensions E' of the facing pieces E of the front pockets reinforce and strengthen the crotches of the side vents, and thus prevent the side 85 seams C of the legs from ripping.

Having thus described my invention, what 85 I claim as new and desire to secure by Letters Patent is:

1. A pair of overalls provided with side 90 vents, front pockets whose rear portions are arranged at the front side of said vents, and facing pieces for the rear portions of said pockets, superimposed upon the front sides of same and provided at their lower ends with integral extensions that extend rearwardly across the lower ends of said side 95 vents and upwardly at the rear side of said vents so as to reinforce and strengthen the side seams of the legs.

2. A pair of overalls having legs formed 100 by front and rear portions joined together by side seams, each leg having a side vent and a front pocket whose rear portion forms the front side of said vent, and a facing piece superimposed on the front face of the rear portion of said pocket and provided at its lower end with an integral extension that extends rearwardly across the lower end of said vent and upwardly over the rear portion of the vent.

3. A pair of overalls provided with side 110

vents whose lower ends terminate at the upper ends of the side seams of the legs, front pockets connected to the front portions of the legs, facing pieces superimposed upon 5 the rear portions of said front pockets and folded over the outer edges of same, and integral extensions on said facing pieces that are secured to the rear portions of the legs in such a way as to reinforce and strengthen 10 the side seams of the legs.

4. In a pair of overalls, a leg formed by front and rear portions connected together by a side seam whose upper end terminates at the lower end of a side vent between said 15 front and rear portions, a pocket provided with a front portion that is connected to the front portion of the leg and a rear portion that forms the front side of said vent, and a facing piece connected to the rear portion

of said pocket so as to serve as a binding 20 for the edge of same and provided with an integral extension that extends across the crotch of said side vent and which is secured to the rear portion of the leg.

5. In a pair of overalls, a leg comprising 25 front and rear portions connected together by a seam and having a vent in proximity to a front pocket carried by the front portion of the leg, a facing piece folded over, the longitudinal side edge of the rear portion 30 of said front pocket and partially covering the front face of said rear portion and an integral extension on said facing piece that is folded over and stitched to the rear portion of the leg in such a way that it reinforces and strengthens the lower end of said 35 vent.

FORREST FERGUSON.
